UNITED STATES PATENT OFFICE.

CHARLES F. PYM, OF ESSEX, ONTARIO, CANADA, ASSIGNOR TO KRENTLER-ARNOLD HINGE
LAST COMPANY, OF DETROIT, MICHIGAN, A CORPORATION OF WEST VIRGINIA.

LINK-LAST.

No. 872,972.

Specification of Letters Patent.

Patented Dec. 3, 1907.

Application filed July 11, 1907, Serial No. 383,227.

To all whom it may concern:

Be it known that I, CHARLES F. PYM, a subject of the King of Great Britain, and resident of Essex, in the county of Essex and Province of Ontario, Canada, have invented an Improvement in Link-Lasts, of which the following description, in connection with the accompanying drawings, is a specification, like letters on the drawings representing like

parts.

My invention is a divided last for use in connection with boots and shoes, and relates to that class of lasts in which the forepart and heel-part are joined by two hinges or unions, covered broadly in the Goding patent, No. 674,084 of May 14, 1901, my last employing a link form of connection, one type of which is shown in the companion Goding patent, No. 674,085.

My object is to provide a last of the above character in which the forepart and heel-part are separated by an oblique line of cut extending from the top obliquely rearward to the bottom, so constructed that it will begin to shorten immediately upon moving toward collapsed position, having no tendency or possibility of lengthening any whatever in moving from its fully open or operative position to its closed or collapsed and shortened position, a further object being to provide a construction which permits the heel-part to slide along the forepart in direct contact therewith if desired, although not necessarily so, and to the above ends, I provide two hinge-plates or articulated unions in the form of pivoted links set one vertically above the other in the last, the pivots of both unions in the heel-part being preferably at the same distance apart as the pivots in the forepart, and located higher, or at least as high, in the heel-part as those in the forepart. In other words, the pivots are preferably in parallel planes extending obliquely downward and forward in the last, and the connecting hinges stand above each other and are intermediate pivoted or articulated between their ends, the latter being pivoted respectively in the opposite parts of the last.

In the drawings, Figures 1 and 2 represent the last in side elevation, the side being broken out or sectioned to show the joint construction more clearly, Fig. 1 showing the last in its lengthened or operative position, as in a shoe, and Fig. 2 showing the last in its shortened or collapsed position.

It will be understood that I have not herein attempted to show the last provided with all its usual trimmings, but have confined my drawing to the invention in hand. The secant line 1 which separates the forepart 2 from the heel-part 3 extends from a point 4 in the crown or upper instep portion of the last downwardly and rearwardly to a point 5 near the rear end of the shank of the last, and while this secant line may be in one or more planes, I prefer to locate an offset 6 therein slightly above the middle of the last, so that when the last is in operative position, with the parts extended as in Fig. 1, the bottom alignment of the forepart and heel-part 70 will be controlled mainly by the offset 6, which relieves the hinges of most of the strain, this being more particularly the case when the last is used in inverted position, as is customary in the manufacture of shoes. 75 Opposite kerfs or recesses 7, 8 are provided, extending longitudinally into the opposite last parts, and in these are mounted a top pair of links 9, 10, and a bottom pair of links 11, 12, pivotally connected at their inner ends 13, and preferably provided with stops 14, which tend to prevent the pairs of links from getting on a dead center, the upper pair of links or hinge union being secured at its opposite ends by transverse pins or bolts 15, 16, and the lower pair of links or hinge union being connected by similar transversely extending pins 17, 18. I have shown the links at practically the extreme upward angle of mounting, but it will be understood that the mounting of the links is not confined to this angle, as the intermediate pivoting of the links so as to make an articulated bond or union makes it absolutely impossible for the heel-part to lengthen in sliding upwardly 95 from its position Fig. 1 to its collapsed position Fig. 2, even though the rear pivots 16 and 18 were located much lower than as shown. Also, while the preferred and most advantageous construction is that in which 100 the upper pair of pivot pins are exactly parallel to the lower pair of pivot pins, the intermediate pivoting of the links causes the last to work properly irrespective of whether the pivot pins are parallel or not.

One of the chief advantages of a second last is to have the heel-part leave the counter-lining instantly upon the very first movement of the last in the shoe when it is to be removed therefrom, and on the other hand, 110

when the last is being inserted in a shoe, to have the heel-part approach and engage the lining at the counter of the shoe horizontally or straight ahead without any sliding movement on said lining. These results are attained in a marked degree by my invention, inasmuch as the intermediately pivoted links yield automatically to whatever position the heel-part may be required to assume in its removal or insertion into a shoe. If the stops 14 are employed, there is never any danger of the hinge connections getting on a dead center so as to compel the heel-part to swing on the forepart, although if these stops 14 are not used there is still very little danger of said swinging movement, because the links tend to drop into a bent position naturally. I prefer to employ the stops 14 and thereby to compel the links to break in opposite directions, as this gives greater strength and bracing effect. I also prefer to locate the links or unions at least as far apart as they are shown in the drawings, as this gives maximum strength against the twisting or shifting strains which are referred to more particularly in the Goding patent No. 674,084, and which render it advisable to employ two links or unions (as therein claimed) instead of one. In use, the last, in its collapsed position Fig. 2, is inserted in the shoe, and then directly vertical pressure is brought upon the heel-part, which causes it to descend into the heel of the shoe in direct sliding contact with the forepart and without any swinging action. The links yield at their pivots 13, permitting the maintenance of this sliding contact without compelling the heel-part to leave or get out of contact with the forepart. The result is that the surface of the heel-part of the last engages the lining or inner surface of the heel-part of the shoe with a direct outward thrust, and substantially without any sliding or downward frictional pressure on said lining whatever. This secures an entire absence of any tendency to disturb or wrinkle, tear or roughen said lining. On the other hand, when the last is to be removed from the shoe, being then in its ex-

tended position the same as shown in Fig. 1, and tightly engaging the inner surface of the shoe at all points, the heel-part is forced forward and upward in sliding contact along the line 1, the result being that the heel-part of the last leaves the lining of the heel-part of the shoe almost solely by a forward movement, and without any tendency to scrape or slide upward on the lining surface of the heel-part of the shoe. The arrangement of the intermediately pivoted links permits this direct forward movement of the heel-part and the continued maintenance of sliding contact between the heel-part and forepart as the last changes from lengthened position Fig. 1 to shortened position Fig. 2, and vice versa. I make no claim to the use of the link form of connecting union, broadly considered, as that form of connecting device has long been commonly known in this art, see for example Clark patent, No. 534,856, and Fitz patent, No. 632,994.

Having described my invention, what I claim as new and desire to secure by Letters Patent is:

1. A hinged last, comprising a forepart and heel-part transversely severed obliquely toward the bottom of the heel-part, and two pairs of links located one above the other for joining said last parts, the links of each pair being pivoted together and pivotally secured respectively in the respective last parts.

2. A hinged last, comprising a forepart and heel-part joined by two intermediately articulated unions pivotally secured at their opposite ends in the respective last parts one above the other, said unions being capable of flexing in opposite directions as the last parts move from one position to the other.

In testimony whereof, I have signed my name to this specification, in the presence of two subscribing witnesses.

CHARLES F. PYM.
